[57] CLAIM

The ornamental design for apparatus for locating the center of gravity of a golf ball, as shown and described.

DESCRIPTION

FIG. 1 is a front and top-right perspective view of an apparatus for locating the center of gravity of a golf ball showing my new design;

FIG. 2 is a top plan view thereof;

FIG. 3 is a bottom plan view thereof;

FIG. 4 is a front elevational view thereof;

FIG. 5 is a right side elevational view thereof, the left side view being a mirror image thereof;

FIG. 6 is a rear elevational view thereof;

FIG. 7 is a cross-sectional view thereof as taken from line VII—VII of FIG. 4.

FIG. 1**FIG. 2****FIG. 3****FIG. 4****FIG. 5****FIG. 6****FIG. 7**
